UNITED STATES PATENT OFFICE.

EDWARD R. SOLEAU, OF NEWARK, NEW JERSEY, ASSIGNOR OF ONE-HALF
TO ISAAC F. ROE, OF SAME PLACE.

HEATING APPARATUS.

SPECIFICATION forming part of Letters Patent No. 521,348, dated June 12, 1894.

Application filed December 1, 1893. Serial No. 492,432. (No model)

To all whom it may concern:

Be it known that I, EDWARD R. SOLEAU, a citizen of the United States, residing at Newark, in the county of Essex and State of New Jersey, have invented certain new and useful Improvements in Heating Apparatus; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

My present invention relates to a new and useful hot water heater for general heating purposes, which may also be used as a steam generator, the invention having for its object to facilitate the heating of the water in a very effectual manner.

The invention therefore consists in novel features of construction and improvements hereinafter described and finally embodied in the clauses of the claim.

The invention furthermore consists in the general arrangement and construction of sections of pipes and headers, adapted to be placed side by side and connected one with the other, whereby a heater is the result, which can be made up of any number of such sections to suit the requirements of the building to be heated.

The invention further consists in the general arrangement and construction of parts and of the "piping" for the purpose of hastening the heating process and causing an increased circulation of water.

The invention is illustrated in the accompanying sheets of drawings, in which—

Figure 1 is a front view of the water heater. Fig. 2 is a horizontal section of the same, taken on line *x* in Fig. 4. Fig. 3 is a vertical cross-section of the heater, and Fig. 4 is a vertical longitudinal section of the same, both of said last-named views clearly illustrating the general arrangement of the heating sections comprising the heater. Fig. 5 is a view similar to that illustrated in Fig. 3, with slight modifications in the pipes and the addition of a steam dome, whereby the heater is adapted as a steam generator. Fig. 6 is a longitudinal vertical section, and Fig. 7 is an

end view of a header of a slightly modified form of construction from that illustrated in Figs. 2, 3 and 4. Fig. 8 is a longitudinal vertical section of two fittings used in connection with the heater sections, and a slip-nipple, illustrating one manner of connecting two of such sections, and Fig. 9 is a vertical section, taken on line *y* in said Fig. 8.

Similar letters of reference are employed in each of the said above described views to indicate corresponding parts.

I preferably construct my novel form of heating apparatus in a rectangular form, as illustrated in the drawings, within a suitable setting of brick, provided at the front with an iron front plate.

In said drawings, *a* indicates the brick wall, which, as will be seen from the several figures of the drawings, forms the back and sides of the heater, being provided with a suitable iron front plate *b*, while the setting for the heater may be provided with a bridge wall *a'*, if desired, which has many advantages as will be more fully stated hereinafter. Said plate *b* is provided with the usual form of doors or openings, and is secured to the front of the brick setting by suitable anchor bolts *a*², as will be seen from Figs. 1, 2 and 3, whereby the said front wall can be easily and quickly removed when it is desired to clean or repair the heating apparatus within the brick wall.

A is the combustion chamber, *a*³ the ash-pit and *a*⁴ is the smoke pipe, which is preferably placed in the rear wall, as shown in Fig. 4, but may be arranged in any other convenient position. Said smoke-pipe is provided with a damper *a*⁵, substantially as shown.

Within the combustion chamber I arrange the heating apparatus, which comprises there-in any suitable number of heating sections *C*. The sections, as shown, consist essentially of a series of T-fittings *c*, each provided with a screw-threaded throat *c'*, and having perforated lugs or ears *c*² at the ends 95 and on opposite sides of said fittings. Any number of such fittings *c* are placed end to end, as illustrated in Figs. 4, 5 and 8, being preferably secured or connected together by means of the usual form of slip-nipple *c*³, as 100 clearly illustrated in said Fig. 8. As will be seen from Figs. 3 and 4, a series of such T-fit-

tings *c* are placed on each side of the ash-pit along the sides of the brick setting and are then securely held together by means of tie-rods *d* which are passed through said perforated ears or lugs *c*², and the several fittings are tightened up by the nuts *d*' on the screw-threaded ends of said tie rods. The first of said fittings *c* in each section is plugged up with a suitable cap or plate *c*³ and from the last fitting in each section on the sides of the ash-pit extend the return-pipes *l* and *l*' for bringing the return water from the building back into the heater. Within each throat *c*' of said fittings *c* is screwed a vertical pipe or tube *e*, provided at their free ends with elbows *e*' from which extend toward the central line of heater, pipes *e*² inclined upwardly at an angle to the plane of the base of the heater. Said inclined pipes or tubes *e*² extend to near the middle of the heater, as shown in Figs. 3 and 5, and are provided with suitable elbows *e*³ from which extend the vertical pipes or tubes *e*⁴, which terminate and are secured in openings in the under side of suitable header *f*. Said headers are preferably corrugated, as illustrated in Fig. 2, whereby, when they are placed side by side, as shown, the heat from the fire can pass between them, thereby allowing freedom of expansion and greater heating surface.

Depending from the lower surface of each header *f* are any suitable number of drop or pendent tubes *f*', which, as will be seen from the several figures, project down to near said inclined pipes or tubes *e*² and are closed at the bottom. Said drop tubes *f*' may be of any desired construction, being preferably of the form and construction illustrated in my previous Letters-Patent, issued December 19, 1893, and numbered 511,280. In the upper side and in the middle of each of said headers, communicating with the inside of the headers, I secure short pipes *f*², each of which is tapped into the throat *g*', of T-fittings *g*, similar to the fittings *c* described in the above. Said fittings *g* are secured together to establish communication with one another, in the same manner as the fittings *c* shown in Fig. 8, and are securely held in place by means of the tie-rods *h* passed through perforated ears or lugs *g*² on the opposite sides of said fittings, being held in place by the nuts *h*' on the screw-threaded ends of said rods *h*. The first of said fittings *g* is plugged up with a suitable cap or plate *g*³ and from the last fitting in said series extends an outlet pipe or tube *i* which leads through the building and finally terminates in the return pipes *l* and *l*' terminating in the last one of the fittings *c* in each series at the sides of the ash-pit, as has been stated in the above. As will be seen from Figs. 3 and 4, some of said pipes or tubes *e* may be provided with an ordinary T-joint *k* which are connected by a pipe *k*' for the water to pass through the same, and upon which the grate bars *m* may be placed. Said pipes, however, may be dispensed with and

the grate-bars can be placed in the heater in any other well known manner.

In lieu of the headers *f* and the independent pipes *f*² and the independent fittings *g*, said pipes and fittings may be dispensed with, and said headers may have a suitable connection *f*³ formed integral with the body portion of the header, said connection expanding at the top, thereby forming a section *f*⁴, as will be clearly seen from Figs. 6 and 7. In the opposite sides of said sections *f*⁴ are formed the holes *f*⁵, whereby any two of such headers and their sections *f*⁴ can be secured together by means of a slip-nipple in the manner of the T-fittings *c* or *g*, as will be evident. Said sections *f*⁴ may be provided with perforated ears or lugs *f*⁶, for holding the sections and the headers connected therewith in position, by means of suitable tie rods. Sometimes the headers themselves may be provided with ears or lugs *f*⁷, in which can be arranged suitable tie rods for securing the headers in place, as will be understood.

By the general arrangement and construction of the several parts comprising my novel form of heating apparatus hereinabove described, it will be seen that I have produced a cheaply constructed and very efficient water heater, in that the several parts can be conveniently handled and put together very quickly. Then again, should any one of the sections become disabled, by removing the tie bolts, any three sections can be disconnected, the disabled section can be removed, and a new one put in position to replace it, and the whole apparatus again steadied by replacing the tie rods. Thus, it is not necessary to disturb the general arrangement and construction of the heater.

A very great advantage is derived by the arrangement of the tubes or pipes *e*² running to the center of the headers *f*, whereby a better circulation and supply of water to said headers and hence to the outlet pipe *i* is the result.

By the arrangement of the removable front plate *b*, said plate can be quickly taken off, and the whole inside apparatus exposed to view, and can be removed from the brick setting without tearing down the brick work. Said front plate *b* is provided with any suitable number of doors *b*' and openings, whereby the ashes can be removed, fresh coal supplied to the fire, and by the arrangement of the large door *b*² and the door *b*³ above it, the heating apparatus can be inspected at any time.

The arrangement of the bridge wall *a*' has the advantage that the heat and gases of combustion are retained above the fire and in direct contact with the heating apparatus, the gases being consumed and there can be no disagreeable odors escaping from the furnace.

By my novel arrangement of the heating sections *C*, it will be seen that with a decreased area of space a large increase of heat-

ing surface and hence of heat is obtained, thereby resulting in a very efficient heater, and one which is especially adapted for buildings cramped for space.

5 Of course it will be readily perceived that any number of sections C can be placed side by side and the efficiency and power of the heater can be greatly increased.

When it is desired to use my heating apparatus as a steam generator, I connect the pipes e and the inclined pipes e² with a vertical pipe or tube e⁵, by means of a T-connection e⁶, as illustrated in Fig. 5. Said pipe terminates in the under side of the header f, and thereby, a circulation of the water is caused through the headers f, pipes e⁵, e² and e⁴, as will be understood. In this case, however, the T-fittings g are dispensed with and the headers f are in direct communication 20 with a steam dome or reservoir n with which the outlet pipe i is in direct communication. Thus, this form of heater is well adapted for the purposes of an efficient steam generator.

It is evident that various changes of construction and in the several arrangements of the "piping" may be made without departing from the scope of my present invention, and hence I do not wish to be understood as limiting myself to the mechanical construction of 30 the several parts herein shown and described.

Having thus described my invention, what I claim is—

1. A heating apparatus provided with a series of sectional fittings c, pipes e extending from said fittings, angularly arranged pipes e² connected with said pipes e, pipes e⁴ connected with said pipes e², and headers f on said pipes e⁴, said fittings c being connected, and arranged on each side of the ash-pit 35 along the sides of the brick setting to form a support for the apparatus, substantially as and for the purposes set forth.

2. A heating apparatus provided with a series of sectional fittings c, tie-rods d, headers f, and connecting pipes or tubes connecting said fittings with said headers, said fittings c being connected, and arranged on each side of the ash-pit along the sides of the brick setting to form a support for the apparatus, substantially as and for the purposes set forth.

3. A heating apparatus provided with a series of sectional fittings c, tie rods d connecting said fittings, pipes e extending from said fittings, angularly arranged pipes e² connected with said pipe e, pipes e⁴ connected with said pipes e², and headers f on said pipes e⁴, said fittings c being connected, and arranged on each side of the ash-pit along the sides of the brick setting to form a support for the apparatus, substantially as and for the purposes set forth.

4. A heating apparatus provided with a series of sectional fittings c, headers f, connecting pipes or tubes connecting said fittings 65 with said headers, sectional fittings connected with said headers, and an outlet pipe connected with said fittings, said fittings c being

connected, and arranged on each side of the ash-pit along the sides of the brick setting to form a support for the apparatus, substantially as and for the purposes set forth.

5. A heating apparatus provided with a series of sectional fittings c, pipes e extending from said fittings, angularly arranged pipes e² connected with said pipes e, pipes e⁴ connected with said pipes e², headers f on said pipes e⁴, sectional fittings connected with said headers, and an outlet pipe connected with said fittings, said fittings c being connected, and arranged on each side of the ash-pit along the sides of the brick setting to form a support for the apparatus, substantially as and for the purposes set forth.

6. A heating apparatus provided with a series of sectional fittings c, tie rods d, headers f, connecting pipes or tubes connecting said fittings with said headers, sectional fittings connected with said headers, tie rods for holding said sectional fittings together, and an outlet pipe connected with said fittings, said fittings c being connected, and arranged on each side of the ash-pit along the sides of the brick setting to form a support for the apparatus, substantially as and for the purposes set forth.

7. A heating apparatus provided with a series of sectional fittings c, tie rods d, pipes e extending from said fittings, angularly arranged pipes e² connected with said pipes e, pipes e⁴ connected with said pipes e², headers f on said pipes e⁴, sectional fittings connected with said headers, tie rods for holding said fittings together, and an outlet pipe connected with said fittings, said fittings c being connected, and arranged on each side of the ash-pit along the sides of the brick setting to form a support for the apparatus, substantially as and for the purposes set forth.

8. The herein described heating apparatus comprising therein a brick setting having a bridge wall a', a series of sectional fittings c, arranged on both sides of the ash pit, means for securing said fittings together, vertical pipes or tubes extending from said fittings, angularly arranged pipes connected with said vertical pipes, extending in pairs toward one another, vertical pipes connected with said angularly set pipes, headers connected with said pipes, and sectional fittings g connected with said headers, provided with means for securing them together, said fittings c being connected, and arranged on each side of the ash-pit along the sides of the brick setting to form a support for the apparatus, substantially as and for the purposes set forth.

9. A heating apparatus provided with a series of sectional fittings c, headers f, connecting pipes or tubes connecting said fittings with said headers, and drop tubes or pipes depending from said headers, said fittings c being connected, and arranged on each side of the ash-pit along the sides of the brick setting to form a support for the apparatus, substantially as and for the purposes set forth.

10. A heating apparatus provided with a

series of sectional fittings *c*, pipes *e* extending from said fittings, angularly arranged pipes *e*² connected with said pipes *e*, pipes *e*⁴ connected with said pipes *e*², headers *f* on said pipes *e*⁴, and drop tubes or pipes depending from said headers, said fittings *c* being connected, and arranged on each side of the ash-pit along the sides of the brick setting to form a support for the apparatus, substantially as and for the purposes set forth.

11. A heating apparatus provided with a series of sectional fittings *c*, headers *f*, connecting pipes or tubes connecting said fittings with said headers, drop tubes depending from said headers, sectional fittings connected with said headers, and an outlet pipe connected with said fittings, said fittings *c* being connected, and arranged on each side of the ash-pit along the sides of the brick setting to form a support for the apparatus, substantially as and for the purposes set forth.

12. A heating apparatus provided with a series of sectional fittings *c*, pipes *e* extending from said fittings, angularly arranged pipes *e*² connected with said pipes *e*, pipes *e*⁴ connected with said pipes *e*², headers *f* on said pipes *e*⁴, drop tubes or pipes depending from said headers, sectional fittings connected with said headers, and an outlet pipe connected with said fittings, said fittings *c* being connected, and arranged on each side of the ash-pit along the sides of the brick setting to form a support for the apparatus, substantially as and for the purposes set forth.

In testimony that I claim the invention set forth above I have hereunto set my hand this 28th day of November, 1893.

EDWARD R. SOLEAU.
